UNITED STATES PATENT OFFICE.

CHESTER C. SMALL, DECEASED, LATE OF NEWTON HIGHLANDS, MASSACHUSETTS; BY JENNIE M. SMALL, ADMINISTRATRIX, OF NEWTON HIGHLANDS, MASSACHUSETTS, ASSIGNOR TO UNITED SHOE MACHINERY CORPORATION, OF PATERSON, NEW JERSEY, A CORPORATION OF NEW JERSEY.

COMPRESSING MACHINE.

Application filed September 16, 1918. Serial No. 254,287.

To all whom it may concern:

Be it known that CHESTER C. SMALL, late of Newton Highlands, in the county of Middlesex and State of Massachusetts, deceased, invented certain Improvements in Compressing Machines, of which the following description, in connection with the accompanying drawings, is a specification, like reference characters on the drawings indicating like parts in the several figures.

This invention relates to compressing machines and the specific embodiment of the invention hereinafter described and illustrated in the accompanying drawings is particularly adapted for compressing or condensing top lifts for the heels of boots or shoes, although it should be understood that many of the features of the invention are equally applicable to machines organized for molding, by compression, other sole leather blanks, such for example as heels.

A type of machine heretofore in extensive commercial use for compressing or condensing heels and top lifts is illustrated in United States Patent No. 776,823, granted December 6, 1904, upon the application of Charles L. Allen. In machines of the type disclosed in the Allen patent a single compressing mold is provided and a single blank is operated upon at a time. While the product of this machine is of very superior quality and the machine has been exceedingly successful commercially, the enormous increase in the use of compressed heels and condensed top lifts has made it desirable that the machine capable of doing the same class of work and having an even greater productive capacity be produced.

The object of the present invention then is to produce a compressing machine capable of producing compressed or condensed blanks such as heels, top lifts or the like of superior quality at a very high rate of speed. In pursuance of this object an important feature of the invention consists in the provision of a plurality of oppositely facing blank confining molds in combination with oppositely moving means for simultaneously exerting upon blanks in the said molds an extremely heavy positive compressing or condensing pressure exerted at one time over the entire areas of the blanks. In a convenient embodiment of this feature of the in-

vention the molds are held in the opposite parallel faces of a rigid mold support and great pressure is applied to the faces of the blanks confined in the molds by dies moved preferably by toggle mechanism into operative engagement with the blanks. In this connection a further feature of the invention consists in the provision of automatic wedge operating mechanism for ejecting the compressed or condensed blank from the mold, operating in timed relation to and preferably as the result of the reciprocating movement of the cross head upon which the mold is carried.

Further features of the invention reside in the provision of means for feeding the blanks in vertical disposition to the compressing mold and means for feeding simultaneously a plurality of such blanks to a plurality of molds.

Further features of the invention of greater or less importance will become apparent upon a reading of the following detailed description of one practical embodiment thereof in connection with the accompanying drawings and the exact scope of the invention will be defined in the appended claims.

In the drawings,—

Figure 1 is a view in side elevation of a compressing machine embodying the invention;

Fig. 2 is a view in front elevation, partly in section, of the head portion of the machine;

Fig. 3 is a perspective view showing the compressing mold and blank feeding mechanism; and

Fig. 4 is a plan view, partly in section, of a detail of the blank feeding mechanism.

Referring now to the drawings, 10 indicates the frame which supports the various elements of the gearing and operating mechanism. A cross head 12 is guided for vertical sliding movement on suitable ways formed upon the frame 10. Operative movement is imparted to the cross head by a toggle 14, 16 stepped at its lower end in the frame and connected at its upper end to the reciprocable cross head 12. The center of the toggle is connected by a connecting rod 18 to a crank shaft 20 which in turn is actuated by power received by a driving pulley

22 mounted upon a driving shaft 24 and connected by transmission gearing 26 to the crank shaft. This general type of mechanism is common in heel compressing and top 5 lift compressing machines and, therefore, need not be described in greater detail.

Projecting forwardly from the cross head 12 is a bracket 28 which supports the mechanism for feeding blanks to the compressing 10 molds. Inasmuch as the feeding and compressing mechanism is duplicated symmetrically with relation to a central vertical plane extending from front to rear of the machine, it will be adequate to describe in detail 15 the construction and operation of the mechanism upon one side of said central plane.

A mold support 30 is mounted rigidly upon the cross head 12 and is recessed in 20 its parallel opposite faces to receive two edge molds 32 which may be identical or may differ in size and contour in accordance with the requirements of the work to be operated upon.

25 The edge mold 32 surrounds an ejector plate 34 which, in addition to its function in ejecting the compressed blank from the mold, serves as the bottom plate or die of the compressing mold. The ejector plate 30 is backed up by a multiple wedge 36 which co-operates with a corresponding 35 normally stationary multiple wedge 38 depending from the head portion 40 of the machine frame. Nuts 42 provide for vertical adjustment of the wedge member 38, variably to regulate the timing of the operation of the ejector plate 34. It will be apparent from an inspection of Fig. 2 that as the mold moves upwardly, the wedge 40 members 36, 38 will co-operate to permit the ejector plate 34 to recede into the edge mold 32, forming a cavity for the reception of the blank to be compressed and conversely, when the cross head and mold descend, 45 the wedge member 36 will be forced outwardly, causing the plate 34 to eject the compressed blank from the mold cavity.

For the purpose of securing the great 50 pressure necessary for molding and condensing the blank, the following mechanism is provided: A follower 44 is guided for horizontal sliding movement transversely of the machine upon the upper end of the cross head 12. A follower die 46 secured 55 to the follower is disposed in parallel relation to the plate 34 and serves to engage and exert pressure upon the outer face of the blank in the mold. Parallel links 48, 50 are pivoted to the follower 44 at 52, 54 60 respectively. The outer ends of these links have lost motion connections with stationary studs 56, 58 mounted in the head 40 of the machine frame. By virtue of this construction, it will readily be seen that rising 65 movement of the cross head 12 will effect a

corresponding inward movement of the follower to apply pressure to a blank in the mold and vice versa. The provision of the parallel links 48, 50 ensures that the follower die 46 shall always be maintained accurately in an upright position and that an easy sliding movement of the follower upon the cross head shall occur in response to the up and down movement of the latter.

The feed carriage 60 is mounted to slide 75 forwardly and rearwardly of the mold in horizontal parallel guideways 62 formed in the bracket 28. In the advance end of the slide 60 is mounted a block 620 (Figs. 3 and 4) in which are pivoted blank feeding 80 fingers 66 held yieldingly by springs 67 against guiding faces 68 formed upon the inner ends of shelf members 70, the horizontal portions of which serve to support the stock of blanks being fed to the machine. 85

Fingers 72 for engaging the upper edges of the blanks are secured to a rock shaft 74 journaled in bearings in a bracket 76 projecting upwardly from the slide 60. A rocker arm 78 secured to the shaft 74 is 90 connected by a rod 80 embodying an adjustable turn buckle 82 to an auxiliary slide 84 mounted for limited reciprocatory movement in the slide 60. The advance end of the finger 72 is turned downwardly, as 95 shown at 86, to engage the curved edge of a blank 88 to be fed to the mold, and then upwardly, as shown at 90, to form an abutment for engaging and removing the previously compressed blank prior to the introduction of a fresh blank to the mold. 100

As a result of the above described mounting of the fingers 72, each one may be moved in a vertical plane closely adjacent to the face of an upright plate 92 against 105 which the blank 88 is placed manually in position to be engaged by the feeding mechanism. For the purpose of producing this pivotal motion of the fingers 72, also the bodily movement of the entire feeding 110 mechanism into and out of the machine, a stationary cam 94 is bolted to a bracket 96 secured to the machine frame 10. A cam lever 98 pivoted to the bracket 28 at 100 carries at its lower end a cam roll 102 arranged to travel in the cam 94. The upper end of the cam lever 98 is yieldingly connected by a spring 106 to a lever 108 also pivoted on the stud 100. Co-operating lugs 110, 112 upon the levers 98 and 108 respectively serve to limit positively their relative movement in one direction while permitting relative yielding movement in the opposite direction against the tension of the spring 106. The upper end of the lever 108 is connected by a link 114 to a lug 116 projecting downwardly from the auxiliary slide member 84. Swinging movement of the lever 108 produced by the travel of the roll 102 in the cam 94 thus causes to and fro move- 115 120 125 130

ment of the auxiliary slide 84, and through it, of the main feed carriage slide and the feeding mechanism carried thereby.

The operation of the machine is as follows: Let it be assumed that the machine parts are in the position illustrated in Fig. 3, that is, with the feed carriage in blank receiving position and the molds closed. The supply of blanks to be operated upon by the machine will be sustained by the shelves 70, of which there is one upon each side of the feed mechanism. The operative, using both hands, picks up a blank from each pile and places the two blanks thus selected flat against the vertical faces of the plates 92, the blanks occupying the positions shown in Fig. 3. It will be understood that at this time the cross head 12 is in its uppermost position and the cam roll 102 at the top of the cam slot 94. As the cross head descends, the roll is actuated by the stationary cam to swing the arm 108 inwardly, carrying with it the feed carriage. As will be apparent from an inspection of Fig. 3, a substantial amount of relative longitudinal movement between the slide 84 and the slide 60 is possible. Initially, the slide 84 moves inwardly of the machine until it engages the face of the bracket 76, the slide 60 being held stationary by the frictional engagement of spring pressed plugs 120 mounted therein with the guides 62. This initial movement of the slide 84 operates through the rod 80 and the rocker arm 78 to lower the fingers 72 to the position shown in dotted lines, in which position each finger engages the edge of the corresponding blank. By the provision of the turn buckle 82 adjustment of the movement of the fingers 72 is made possible to the end that they shall properly engage blanks of various dimensions. Longitudinal adjustment of the block 620 relatively to the slide 60 for the purpose of adjusting the fingers 66 properly to engage the blank is effected by a screw 63 threaded through the block 620 and held against longitudinal movement in the slide 60. A conveniently arranged knob 65 serves to rotate the screw.

After the slide 84 engages the face of the bracket 76, the continued inward movement of the lever 108 is translated into feeding movement of the feed carriage slide 60 and the feeding mechanism carried thereby. The two blanks 88 are thus fed into the spaces 122 between the plates 34 and their corresponding follower dies 46. In this feeding movement the previously condensed blanks are pushed out of the way by the upturned ends 90 of the fingers 72, dropping into the discharge chute 124. The downward movement of the wedge member 36 upon the stationary wedge member 38 will have projected the ejector plate 34 to eject the condensed blank into the path of the upturned

end 90 of the finger 72 when said upturned end arrives in position to discharge the finished blank to the chute.

When the cross head shall have reached the lower limit of its movement, the roll 102 will be at the bottom of the cam slot 94 and each blank will have been fed into register with one of the molds. As the cross head starts upwardly, the swinging of the lever 108 outwardly first moves the auxiliary slide 84 back to the outer end of the slide 60. This relative movement lifts the fingers 72 until their ends are sufficiently high to clear the blanks during the further retraction of the feeding mechanism to blank receiving position. The upward movement of the cross head also acts to swing the links 48, 50 about the studs 56, 58, thus moving the follower die 46 into engagement with the face of the blank which is fed into the space 122 and forcing the ejector plate 34 and the blank into the edge mold 32. At this time the rise of the cross head will have brought the wedges 36, 38 into such relative position that the ejector plate 34 is permitted to retract.

At the end of the upward movement of the cross head, a very powerful compression and condensation is imparted to the blanks by the follower links upon the two sides of the machine acting in opposition to each other upon the toggle principle. Inasmuch as the movement of the cross head itself is effected also by a toggle, it will be appreciated that an enormous pressure can be exerted upon the work by the application of only a reasonable amount of power to the driving pulley of the machine.

Only one cycle of operation of the machine has been described in specific detail but it will be understood by those skilled in the art that the machine will run continuously, a fresh pair of blanks being supplied to the feeding mechanism by the operative each time the feeding mechanism reaches blank receiving position. Inasmuch as two blanks are operated upon simultaneously in each cycle of the machine's operation, it will be apparent that the capacity of the machine for the production of work is practically doubled as compared with the single mold machines heretofore known in the art; yet the machine itself is little, if any, larger or more complicated than such single mold machines and does not require anything like twice the amount of power used in operating such single mold machines.

Having described the invention, what is claimed as new and desired to be secured by Letters Patent of the United States is:

1. In a compressing machine, the combination of a plurality of oppositely-facing blank-confining molds, and oppositely moving means arranged for relative approach-

ing movement to simultaneously exert pressure upon the entire areas of the oppositely facing blanks confined in said molds.

2. In a compressing machine, the combination of means for supporting a plurality of individual blanks facing in opposite directions and confining them against lateral expansion, and oppositely moving means arranged for relative approaching movement and acting automatically to exert pressure simultaneously over the entire areas of each of said blanks during said movement.

3. In a compressing machine, the combination of means for confining a plurality of individual blanks against lateral expansion in substantially parallel relation, and a corresponding plural number of compression means arranged for relative approaching movement and acting in opposite directions upon the blanks to exert automatically the same pressure simultaneously over the entire areas of all of said blanks during their approaching movement.

4. In a compressing machine, the combination of means for supporting and confining a plurality of blanks with their corresponding faces in parallel spaced relation and oppositely directed, and oppositely moving means for simultaneously exerting pressure upon the entire areas of the opposite outer faces of said blanks.

5. In a compressing machine, the combination of a mold support, blank edge confining molds facing outwardly on opposite sides of said support, means for exerting molding pressure simultaneously upon the opposite faces of blanks confined in the said molds, and means for simultaneously ejecting the compressed blanks from the molds.

40 6. In a compressing machine, the combination of a plurality of molds arranged to receive blanks disposed in substantially vertical planes, means for exerting pressure horizontally upon the blanks, and means for ejecting the compressed blanks from the molds, comprising an ejector plate for each mold, a stationary wedge member and movable wedge members co-operating with the stationary member to actuate the ejector plates.

50 7. In a compressing machine, the combination of a mold arranged to receive a vertically disposed heel blank, and means for automatically feeding a blank in its vertical plane to the mold.

8. In a compressing machine, the combination of a plurality of vertically disposed molds, and means for simultaneously feeding a plurality of blanks to said molds in vertical planes.

60 9. In a compressing machine, the combination of a vertically disposed compressing mold, means for applying pressure to a blank confined in said mold, means for ejecting the compressed blank horizontally

from the mold, and means for discharging the ejected blank and feeding another blank to the mold in a vertical plane.

10. In a compressing machine, the combination of a reciprocating cross head, a plurality of outwardly-facing blank-confining molds, a plurality of oppositely acting dies for exerting pressure upon blanks confined in the molds, and toggle means responsive to the movement of the cross head for simultaneously actuating said oppositely acting dies toward each other to compress the blanks in the molds.

11. In a compressing machine, the combination of a reciprocating cross head, a plurality of oppositely-facing blank-confining molds, a plurality of oppositely acting dies for exerting pressure upon blanks confined in the molds, toggle means responsive to the movement of the cross head for simultaneously actuating said dies, and toggle means for reciprocating the cross head.

12. In a compressing machine, the combination of a reciprocating cross-head carrying a plurality of oppositely facing blank holding molds, a plurality of oppositely acting dies for exerting pressure upon blanks in the molds, and means for moving the dies in opposite directions towards the molds to simultaneously compress the blanks in the molds.

13. In a compressing machine, the combination of a reciprocating cross-head carrying a plurality of oppositely facing blank holding molds, means for feeding a plurality of blanks to said molds, a plurality of oppositely acting dies for exerting pressure upon blanks in the molds, and means for moving the dies in opposite directions towards the molds to simultaneously compress the blanks in the molds.

14. In a compressing machine, the combination of a plurality of oppositely facing blank holding molds, means for feeding a plurality of blanks to said molds, a plurality of oppositely acting dies for exerting pressure upon blanks in the molds, means for moving the dies in opposite directions towards the molds to simultaneously compress the blanks in the molds, and means for simultaneously ejecting the compressed blanks.

15. In a compressing machine, the combination of a reciprocating cross-head carrying a plurality of oppositely facing blank holding molds, means for feeding a plurality of blanks to said molds, a plurality of oppositely acting dies for exerting pressure upon blanks in the molds, means for moving the dies in opposite directions towards the molds to simultaneously compress the blanks in the molds, and means for simultaneously ejecting the compressed blanks.

16. In a compressing machine, the combination of a plurality of oppositely facing molds for holding a plurality of blanks,

oppositely related dies for acting independently upon the blanks in the molds, and means for simultaneously moving the dies oppositely in a direction of approach for compressing the blanks.

17. In a compressing machine, the combination of a reciprocating cross-head carrying oppositely facing blank holding molds, oppositely acting dies for exerting pressure upon blanks in the oppositely facing molds, and means rendered effective by reciprocation of the cross-head for simultaneously operating the oppositely acting dies.

18. In a compressing machine, the combination of a reciprocating cross-head carrying oppositely facing blank holding molds, means for simultaneously feeding a blank to each of the blank holding molds, oppositely acting dies for exerting pressure upon blanks in the oppositely facing molds, and

means rendered effective by reciprocation of the cross-head for simultaneously operating the oppositely acting dies.

19. In a compressing machine, the combination of a mold support having in each of its opposite faces an outwardly facing mold, means for reciprocating the mold support, means for exerting pressure simultaneously upon blanks held in the oppositely facing molds including a mold bottom for each of the molds interposed between the molds, and wedge mechanism for moving the bottoms of the molds simultaneously in opposite directions.

In testimony whereof I have signed my name to this specification.

JENNIE M. SMALL,

Administratrix of the estate of Chester C. Small, deceased.
